UNITED STATES PATENT OFFICE.

JOSEPH C. CRAMP, OF PHILADELPHIA, PENNSYLVANIA, ASSIGNOR OF ONE-HALF TO CHARLES D. CRAMP, OF SAME PLACE.

GARMENT-HOOK.

SPECIFICATION forming part of Letters Patent No. 525,891, dated March 19, 1895.

Application filed September 29, 1894. Serial No. 524,459. (No model.)

To all whom it may concern:

Be it known that I, JOSEPH C. CRAMP, a citizen of the United States, residing in the city and county of Philadelphia, in the State of Pennsylvania, have invented certain new and useful Improvements in Garment-Hooks, of which the following is a specification.

The object of my invention is the provision of a hook of a simple and inexpensive character, and adapted to be easily manually engaged with and disengaged from the eye, but, by virtue of its construction, as hereinafter described, not liable to be accidentally disengaged from it.

15 In the accompanying drawings I show and herein I describe a good form of a convenient embodiment of my invention, the particular subject-matter claimed as novel being hereinafter definitely specified.

20 In the accompanying drawings, Figure 1 is a front or face view of a hook embodying my invention, represented as engaged with an eye. Fig. 2 is a view in perspective of the hook without the eye. Fig. 3 is a front or face view of the hook, showing an eye in the position which it is caused to assume in the act of engagement or disengagement.

Similar letters of reference indicate corresponding parts.

25 Generally stated, my invention comprehends a hook the bill of which, while structurally continuous of the shank, overhangs and exists at an angle (preferably a right angle) with respect to it, the curved portion, bend, or bight, of the hook intermediate between and connective of the said shank and bill existing in a plane approximately horizontal, as a result of which construction the bight of the hook is closed except for the open space 30 between the under face of the bill and the upper face of the shank, and movement of the hook or the eye with relation the one to the other in engagement or disengagement, must be in a direction approximately right angular 35 to the axis of the shank.

My improved hook, which may, of course, be formed of any suitable material, is shown in the drawings, as formed of wire, the body of the hook, comprising the shank, bill, and bend, 40 being formed of a single wire doubled upon itself, and having its end portions curved

away from each other to form the thread eyes, in the usual manner.

In the preferred construction of my improved hook, as shown, the metal forming the outer portion of the shank, is bent laterally, and in approximately a horizontal plane, to form a return curve of any desired radius, which I term the bend of the hook, the end portion beyond the bend, which forms the bill, and into which said bend merges, being extended transversely across, and terminating at any desired distance beyond, the shank.

The bill of the hook, in the form shown in the drawings, while straight in plan or when viewed from the front, is of arciform contour when viewed from the edge, its arch or rise being preferably concentric with respect to the axis of the shank and of sufficient radius to afford the desired clearness to the eye in its entrance beneath and passage along said bill.

70 In its practical employment, my improved garment hook, is placed in engagement with the eye by slipping the eye over the end of the bill, as shown in Fig. 3, and moving the said eye transversely of the shank along said bill until, under the tendency of the opposing edges of the garment to which the hook and eye are respectively applied to draw away from each other, or under the guidance of the fingers of the user, the eye reaches its position of final engagement, as shown in Fig. 1.

75 By virtue of the angular relationship of the bill with respect to the shank, said bill, shank, and connecting bend, form, in plan, a complete circle, the only mouth to or outlet from which is the passage beneath the bill and between it and the shank. When, then, the eye is seated with respect to my improved hook as in Fig. 1, and the opposing edges of the 80 garment to which the hook and eye are respectively applied happen to approach each other, the eye which in an ordinary hook would pass rearwardly out from beneath the bill and become disengaged from the hook, 85 simply presents its rounded end portion or bight against the transversely disposed bill, and is thereby prevented from becoming accidentally disengaged from the hook.

90 The preferred arciform contour of the bill serves to form a curved mouth to the hook through which the eye cannot ordinarily find

its way unassisted, while, the extension of the end of the bill down to a point on a level with the shank, obviates the likelihood of the bill, catching in other garments or the fingers of the user.

While the general arrangement of the hook and the curved contour of its mouth render it impossible under ordinary circumstances for the hook and eye to become accidentally disengaged, yet disengagement may be very readily, easily and certainly effected under the guidance of the fingers of the user.

In the drawings, *A* is the shank of the hook; *a*, the bend; *b*, the bill, and *e* the thread eyes.

C designates the eye.

Having thus described my invention, I claim—

1. A hook consisting of a shank, bend, and bill, the shank and bend being in approximately the same horizontal plane, and the bill being transversely disposed with respect to the shank, substantially as set forth.

2. A hook consisting of a shank, bend, and bill, the shank and bend being in approxi-

mately the same horizontal plane, and the bill being transversely disposed with respect to, and overhanging, the shank, substantially as set forth.

3. A hook consisting of a shank, bend, and bill, the shank and bend being in approximately the same horizontal plane, and the bill being arciform and transversely disposed with respect to the shank, substantially as set forth.

4. A hook consisting of a shank, bend, and bill, the shank and bend lying in approximately a common horizontal plane, and the bill being transversely disposed with respect to the shank and overhanging the same, and having its extremity bent down to a point approximately level with the shank, substantially as set forth.

In testimony that I claim the foregoing as my invention I have hereunto signed my name this 25th day of September, A. D. 1894.

JOSEPH C. CRAMP.

In presence of—

J. BONSALL TAYLOR,
F. NORMAN DIXON.

Correction in Letters Patent No. 535,891.

It is hereby certified that in Letters Patent No. 535,891, granted March 19, 1895, upon the application of Joseph C. Cramp, of Philadelphia, Pennsylvania, for an improvement in "Garment-Hooks," an error appears in the printed specification requiring correction, as follows: In line 70, page 1, the word "clearness" should read *clearance*; and that the said Letters Patent should be read with this correction therein that the same may conform to the record of the case in the Patent Office.

Signed, countersigned, and sealed this 26th day of March, A. D. 1895.

[SEAL.]

JNO. M. REYNOLDS,
Assistant Secretary of the Interior.

Countersigned:

JOHN S. SEYMOUR,
Commissioner of Patents.
